GARMENT HANGER

Samuel Zetlin, Baltimore, Md.

Application February 6, 1937, Serial No. 124,367

4 Claims. (Cl. 223—86)

This invention relates to garment hangers, and especially to the kind that is intended for hanging pants with their upper and lower parts suspended from their intermediate parts that are laid over a tubular supporting member that is adapted to hold disinfecting or fumigating material.

One object of this invention is to provide a garment hanger, of the kind above-mentioned, composed of a very few and comparatively simple parts, so it can be produced and sold at a low cost and adequate profit.

Another object is to provide this type of device with end-closing members that are movable from a position that permits a wire hanger to be moved into and out of a slot, to a position for preventing the wire hanger from accidentally moving out of the slot; also to provide the end-closing members with means to securely lock them in their normal position on the tubular supporting member, the latter being depressible for disengaging it from the locking means and being elastic for returning the depressed portions to the normal cylindrical shape.

Another object is to engage the horizontal part of a one-piece-wire hanger with the cylindrical fumigator receptacle eccentrically with respect to the axial center of the latter, so it will not and cannot rotate on said horizontal part and permit the heavier part of a pair of pants to cause it to turn and drop the pants.

Other objects and important features are pointed out or implied in the following details of description, in connection with the accompanying drawing in which:

Fig. 1 is a perspective view of my invention in the position for supporting a pair of pants.

Fig. 2 is a longitudinal sectional view of one end of the device, the section being along the line 2—2 of Fig. 4.

Fig. 3 is a longitudinal sectional view along the line 3—3 of Fig. 5, showing the fumigator receptacle inverted or in a different useful position from that shown in Figs. 1 and 2.

Fig. 4 is a cross sectional view along the line 4—4 of Fig. 2.

Fig. 5 is a cross sectional view along the line 5—5 of Fig. 3.

Fig. 6 is a cross sectional view along the same line as Fig. 4, but showing the tube depressed for unlocking the end-closing member therefrom so the latter can be slid to the position shown in Fig. 7.

Fig. 7 is a view taken in the same line as Figs. 4 and 6, but showing the slot of the end-closing

member in open communication with the slot of the intermediate or main tubular member so the wire hanger can be put into engagement with the fumigator receptacle which is composed of the main tubular member and the end-closing members.

Referring to the drawing in detail, in which similar parts are referred to by similar reference numerals on the drawing and in the specification, the invention is now described and specified in detail as follows:

A substantially cylindrical or tubular member, 10 of any appropriate flexible and elastic material, is longitudinally slotted at 11, and provided with openings 12 of any appropriate number, size and shape. The member 10 is adapted to contain perfuming and/or fumigating material; and the fumes therefrom can pass through the slot 11 and openings 12 into the fabric of the pants or other garment hung on the garment hanger.

End-closing members 13 are slidably seated but normally locked on the ends of the member 10, and each of these members 13 consists of a disc 14 and a sleeve 15 united in cup-shape and provided with a slot that is shown at 16 and extends diametrically or radially the greater part of the distance across the disc 14, into the adjoining part of the sleeve 15, and out through the end of the sleeve away from the disc. These sleeves and discs are composed of thin but relatively rigid material of any appropriate kind, so they retain the cup-like shape and prevent the slotted member 10 from expanding beyond the cylindrical shape shown; and the slot 16 is preferably the same width as the slot 11 except where it may be slightly narrowed by a locking lug or tongue 17 which is integral with the sleeve 15 and extends into the slot 11 only at times when the horizontal wire 18 is to be passed into or out of the intercommunicating slots as shown in Fig. 7. However, the locking lug is not essentially located at the slot 16, or may be located thereat without extending thereinto.

Normally, the lug or tongue 17 extends into an opening 19 in the member 10, and when in this position, the ends of the slots 11 are bridged or closed by the sleeves 15, so the wire 18 cannot then pass out through the slot 11, but engages the underside of the upper part of the member 10 so as to support the latter and the end-closing members. However, when it is desired to remove the wire 18, the parts of the member 10 adjacent to the openings 19 can be depressed (as shown in Fig. 6) by manipulation of the user so as to free the sleeves from locking

engagement of their lugs 17 with the member 10, thus permitting the sleeves to be turned to the position shown in Fig. 7.

When the wire hanger provides sufficient clearance, the container 10-13 can be inverted, as shown in Figs. 3 and 5, but it may be preferable to retain the normal position shown in Figs. 1, 2 and 4 wherein the locking and unlocking means is convenient for manipulation by thumbs of the user.

When a coat or other sleeved garment is hung on the complete hanger and fumigator shown in Fig. 1, the slots 16 serve as vents or outlets for the fumes from the fumigating material in the receptacle or container 10-13 to pass into the sleeves of such garment, while the discs 14 prevent the unvaporized fumigating material from escaping.

While describing this form of my invention specifically, I have no intention of limiting my patent protection to these precise details of construction and materials, for the invention is susceptible of numerous changes within the scope of the inventive ideas implied and claimed.

I claim as my invention:

1. In a garment hanger, the combination of a tubular member having a slot extending from end to end for permitting an element of a hanger-member to be passed therethrough to the interior of the tubular member, and sleeves movably secured on the ends of said tubular member and normally bridging the slot of the latter, said sleeves each having a slot therein that can be brought into open communication 35 with the slot of said tubular member for per-

mitting said element of said hanger to be disengaged from said tubular member.

2. The combination defined by claim 1, said tubular member having openings therein at points near the ends of the first said slot, said sleeves each having a lug normally extending into one of said openings so as to lock each sleeve in position for bridging the slot of said tubular member, the tubular member being depressible and elastic at points near said openings so the latter can be depressed for moving them out of engagement with said lugs and so the tubular member automatically returns the depressed portions to normal when released.

3. The combination defined by claim 1, each of said sleeves having a disc united therewith and provided with an opening in communication with the slot of the sleeve so as to form a continuation of this slot and to receive said hanger element while these discs substantially close the ends of the sleeve for retaining fumigating material in the tubular member while permitting fumes to pass from the tubular member through the opening of each of said discs, for the purposes specified.

4. The combination defined by claim 1, in combination with a wirehanger which includes a normally horizontal part that extends through the tubular member from end to end in an eccentric or axially parallel position with respect to the axis of said tubular member so as to prevent rotation of the tubular member on said horizontal part.

SAMUEL ZETLIN. 35
